UNITED STATES PATENT OFFICE.

THOMAS P. WALSH, OF BOSTON, MASSACHUSETTS, ASSIGNOR TO WALSH-BAKER CORPORATION, OF PORTLAND, MAINE.

BOBBIN.

957,825.

Specification of Letters Patent. Patented May 10, 1910.

Application filed November 20, 1909. Serial No. 529,055.

To all whom it may concern:

Be it known that I, THOMAS P. WALSH, a citizen of the United States, and resident of Boston, in the county of Suffolk and State 5 of Massachusetts, have invented an Improvement in Bobbins, of which the following description, in connection with the accompanying drawings, is a specification, like characters on the drawings representing like 10 parts.

Great inconvenience and expense have heretofore been occasioned by the fact that there is always left on bobbins a small body 15 of yarn, which is usually unwound or cut away by hand. The ordinary practice is to deliver the bobbins, as they drop from or are removed from the looms, to boys, who cut the yarn remnants from the bobbins by means of sharp knives. The knives necessarily 20 cut into the yarn-receiving surface of the bobbin more or less, thereby roughening the bobbin and soon spoiling it. Aside, however, from the destruction of bobbins, this removal of the yarn bodies from the bobbins 25 is expensive, as the average mill requires a large number of boys constantly performing this unhealthful work.

Accordingly it is the object of my present invention to provide a bobbin which will 30 greatly facilitate the removal of the yarn, even though by hand, and which is primarily intended for use in automatic machines (as explained in my machine application) which handle the bobbins in large numbers, 35 and with great rapidity strips therefrom all the yarn without the slightest injury to the bobbin, thereby saving the large expense mentioned as well as preventing the loss of the bobbins.

Stated in general terms, my invention resides in providing, in the bobbin, a shallow 40 groove, running lengthwise of the bobbin and terminating short of the yarn-delivery end of the bobbin, said groove being preferably lined with a hard substance and preferably also terminating short of the butt end 45 of the bobbin. This groove serves primarily to receive a knife, as above explained, and it also serves as a positioner in conjunction 50 with my machine above explained, and also serves to receive a feeler (said feeler not being further referred to herein as it is reserved for a separate application).

In the drawings, Figure 1 is a plan view 55 of my new bobbin; Fig. 2 shows the same in

central vertical longitudinal section; Fig. 3 is an enlarged cross sectional view thereof; and Fig. 4 is a view similar to Fig. 1 showing my invention applied to a different form of usual bobbin.

The bobbin itself, in its general shape and construction, may be of any usual or preferred kind, being herein shown in Figs. 1 to 3 as comprising a butt end or holding end 1 having a holding groove 2 to cooperate in well known manner with the bobbin case, and the forwardly extending part 3 terminating in a smooth delivery end 4, the bobbin shown in Fig. 4 being a well known kind for use in a different type of loom 70 from that shown in Fig. 1, and containing, instead of a holding groove 2, a plurality of metal bands or rings 5 to aid the positioning of the bobbin. The remnant of yarn which is usually left on a bobbin when the latter is 75 ejected or removed from a loom is indicated at 6. This body of yarn is sometimes large and sometimes small, being at times considerably tangled and at other times even, sometimes being in a compact bunch or heap, 80 and at other times spread out thin as shown in the drawings, the result being that when removed by a knife in the hands of a boy, according to the usual custom, he soon gets into the habit of slashing into the bobbin 85 itself with one or more cuts, more or less ill directed. I have found that by cutting from the inside out the yarn may be instantly removed by a sharp knife without any possibility of injuring the bobbin, this operation, 90 moreover, being positive, so that all the yarn is removed at one cut. This is carried out in my machine above alluded to, in which I provide means to engage a groove in the bobbin for automatically positioning the 95 bobbin with relation to the machine and with relation to the knife, and for also directing the knife.

Accordingly my present invention consists in providing a bobbin with said longitudinal groove as indicated at 7 (which may have any desired cross-sectional shape, with a square, round, pointed or other bottom or not), said groove terminating at 8 back from the extreme end 9 a sufficient distance to leave the surface of the yarn delivery end 4 peripherally smooth and entirely uncut throughout its circumference. Preferably also it slopes upwardly at said point 8. The groove 7 has preferably a uniform depth 105 110

throughout its main length, which is preferably coextensive with the extent of the yarn-receiving surface of the bobbin. I prefer also to have the groove terminate at 10, 5 short of the extreme butt end of the bobbin. These bobbins are usually made of hard wood, such as kiln-dried maple, and hence the unprotected groove will endure a long period, but preferably a sheathing or lining 10 12 of metal or other hard substance is squeezed down into or otherwise secured in the groove, as best shown in section in Figs. 2 and 3, so that the edge of the groove will not become splintered or otherwise roughened or injured in use, but will remain in 15 perfect yarn-receiving condition.

My invention is intended for bobbins of whatever material they may be made.

In use, as the bobbins, which have dropped 20 or been removed from the various looms throughout the factory, are collected, they are taken to my machine, or, it may be, to the hand operator, and a suitably shaped knife is quickly run along the groove 7 beneath the yarn 6, cutting it accurately and 25 instantly entirely away from the bobbin. The blunt back of the knife slides along the bottom of the groove, while the sharp edge of the knife projects obliquely from the 30 groove in exactly the right position to cut the yarn to the best advantage. This entirely eliminates all danger of injury to the bobbins, facilitates the removal of the yarn with great rapidity, and insures that it is all 35 removed alike from all the bobbins. By the term groove, it will be understood that I include any and all slit-like formations capable of receiving and directing a knife, whether shallow or not, and whether extending 40 only partially or entirely through the shell, except when expressly stated to the contrary in the claims. Also it will be understood that by specifying that the groove shall terminate short of the yarn-delivering 45 end of the bobbin, I mean merely that the bobbin shall be provided with a smooth peripheral yarn-receiving end, or in other words, irrespective of how the grooves may be originally made or formed in the bobbin, 50 its open and exposed side at the periphery or yarn-engaged surface of the bobbin shall not extend to the extreme end 9 of the finished bobbin so as to interfere with the proper delivery of the thread or yarn.

55 It is essential that the delivery end 9 of the bobbin shall be perfectly smooth and without slit, cut or indentation throughout its entire periphery in order that the yarn may maintain continuous sliding and whirling engagement around said end as it is pulled axially from the bobbin in the weaving process, and accordingly the groove 7 does not continue throughout the entire length of the bobbin, but, on the other hand, 60 65 it begins as close as practicable to this

smooth delivery end of the bobbin in order that the knife, especially when operated in connection with my machine, may have free movement for a considerable distance before engaging and cutting through the yarn. 70 The yarn remnant always gathers at and adjacent the butt end or holding end 1 of the bobbin at the point where the cylindrical body portion of the bobbin verges or curves outwardly into said butt end, and accordingly this long extent of groove which normally extends beyond said yarn remnant when the spindle has been substantially exhausted of its yarn, serves as a means for giving directed momentum to the knife as 80 its point is quickly slid along said groove on the metal track or lining 12 therein.

Having described my invention, what I claim as new and desire to secure by Letters Patent is:

1. A loom bobbin, provided at its butt end with holding means and thence extending in a long slender yarn-supporting body terminating in a similarly slender smooth delivery-end whose peripheral yarn-engaging surface is uncut and unindented, said slender body having a substantially uniform diameter from said butt end throughout its yarn-receiving extent to said smooth delivery-end, and provided with a longitudinal groove beginning in said uniform-diameter portion of the bobbin adjacent, but not entering, said smooth delivery-end and continuing lengthwise of the slender portion and also lengthwise of at least a part of the 100 butt end of the bobbin, whereby the yarn has free unimpeded axial delivery lengthwise over said smooth delivery-end in continuous whirling contact with its smooth surface, peripherally thereof, and, when all delivered except the usual yarn remnant adjacent the butt end, a long extent of said groove is exposed between said remnant and the said smooth delivery-end, for giving directed momentum to a stripping knife run 110 quickly along said groove for cutting through said remnant.

2. A loom bobbin, provided at its butt end with holding means and thence extending in a long slender yarn-supporting body terminating in a similarly slender smooth delivery-end whose peripheral yarn-engaging surface is uncut and unindented, said slender body having a substantially uniform diameter from said butt end throughout its yarn-receiving extent to said smooth delivery-end, and provided with a longitudinal groove beginning in said uniform-diameter portion of the bobbin adjacent, but not entering, said smooth delivery-end and continuing lengthwise of the slender portion and also lengthwise of at least a part of the butt end of the bobbin, and a metal track permanently lining said groove for the point of a knife to travel on, whereby 120 125 130

the yarn has free unimpeded axial delivery lengthwise over said smooth delivery-end in continuous whirling contact with its smooth surface, peripherally thereof, and, when all 5 delivered except the usual yarn remnant adjacent the butt end, a long extent of said groove is exposed between said remnant and the said smooth delivery-end, for giving directed momentum to a stripping knife run

quickly along said groove for cutting 10 through said remnant.

In testimony whereof, I have signed my name to this specification, in the presence of two subscribing witnesses.

THOMAS P. WALSH.
